UNITED STATES PATENT OFFICE

GILBERT C. ATWILL AND JAY O. BROWDER, OF LA JUNTA, COLORADO, ASSIGNEES OF
ONE-THIRD TO GEORGE RICHTER, OF LA JUNTA, COLORADO

VANITY CASE DESIGNED FOR NIGHT USE

Application filed July 9, 1929. Serial No. 376,885.

This invention relates to pocket and personal use articles and pertains particularly to a vanity case.

The primary object of the present invention is to provide an improved type of vanity case which may be used at night, there being provided, in the construction of the case, means for the insertion thereinto of a small electric battery which is employed to energize an incandescent lamp forming a part of the structure.

A further object of the invention is to provide a vanity case particularly adapted for night use, which is of a compact nature, light in weight and of simple construction, there being few movable or removable parts in the construction thereof.

The invention will be best understood from a consideration of the following detailed description taken in connection with the accompanying drawings forming a part of the present invention with the understanding, however, that the invention is not confined to any strict conformity with the showing of the drawings but may be changed or modified so long as such changes or modifications mark no material departure from the salient features of the invention, as expressed in the appended claim.

In the drawings:—

Figure 1 is a view in plan of the case embodying the present invention, in open condition.

Figure 2 is a longitudinal sectional view taken upon the line 2—2 of Figure 1.

Figure 3 is a sectional view taken upon the line 3—3 of Figure 2.

Figure 4 is a detailed sectional view taken upon the line 4—4 of Figure 1.

Referring more particularly to the drawings wherein like numerals of reference indicate corresponding parts throughout the several views, the numeral 1 indicates generally the bottom of the case embodying the present invention, the top being indicated by

the numeral 2. As shown, the case is of elongated substantially oval construction, the top and bottom sections thereof being hingedly connected at one end, as indicated at 3.

Secured within the bottom section 1 of the case, which section has the surrounding wall 4 at the upper end thereof, is a socket 5 adapted to receive an incandescent lamp 6.

Within the bottom section there is arranged a pair of spaced resilient spring clips 7 and 8 which are designed to resiliently hold in position within this bottom section an electric dry cell 9. The resilient member or clip 7 is connected by a suitable insulated wire 10 with the socket 5 in the manner shown, and by means of this wire current is transmitted from the member 7 to the lamp, this member having contact with the top one of the usual spring arms carried by the dry cell battery of the character employed. One side of the wall 4 of the bottom section is provided with an indented portion 11 of relative thin and flexible or pliable metal, this indented portion being designed to receive a finger and when pressed inwardly is adapted to be brought into engagement with a contact point 12 of the battery to complete an electric circuit therethrough and through the lamp. One side of this indented portion 11 is cut away from the wall 4 from which it is pressed, as indicated at 13 in Figure 4, so that the flexibility of this element will be increased.

Designed to be inserted into the bottom portion 1 of the case is a false bottom comprising a plate 14 which is of the same contour as the vanity case and which has a surrounding flange 15 designed to frictionally engage the inner face of the surrounding portion 4 of the bottom section, in the manner shown in Figure 2, to maintain the false bottom in position over the bottom section of the case and in a plane slightly above the free edge thereof. This false bottom has, at its upper end, a light opening 16 cut therethrough and in alignment with the light opening are two

additional openings 17 and 18 which are designed to receive the receptacles 19 which carry rouge and powder. The top of these receptacles are flanged or otherwise suitably formed to prevent their passing entirely through the openings in which they are placed and the overall diameters of the receptacles are such as to make their engagement in the opening tight so that they will be securely held in position.

The top portion 2 of the vanity case has a wall flange 20 similar to the flange portion 4 of the section 1 and this flange, when the top is closed positions over the bottom portion 15 so that a case of neat appearance is provided. The flange 20 at the front portion of the top is provided with an outstanding button 21 which when the top is closed frictionally receives a similarly formed indentation in the 20 flange of the false bottom 14.

Against the inner face of the top 2 is positioned a mirror held in place by a suitable frame 24 which frictionally engages the inner face of the top flange 20, in the manner shown 25 in Figure 2.

From the foregoing description it will be readily seen that when the case embodying this invention is opened up at night, the user will be provided with ample light to enable 30 her to use the articles within the case, by pressing inwardly upon the flexible portion 11 in the wall of the bottom portion to close a contact between one side of the battery and the metal body of the case, thus energizing 35 the lamp 6.

Sufficient light from the lamp 6 will be thrown upon the face of the user so that the same can be readily seen in the mirror 23.

Having thus described our invention, what 40 we claim is:—

A vanity case comprising a top and a bottom section each having a surrounding wall flange, hinge means connecting said sections and facilitating the bringing together of the same 45 in wall edge opposed relation, a false bottom comprising a flat body of substantially the same contour as the bottom section and a surrounding flange adapted to be inserted into the bottom section and frictionally engage the 50 flange portion thereof, said false bottom and flange being of a width greater than the depth of the bottom section whereby the flat portion of the false bottom is maintained above the bottom section, said false bottom having 55 an aperture through the flat portion thereof and further forming a chamber with the bottom section, an electric incandescent light in said chamber in a position for exposure through said aperture, means for removably 60 securing an electric battery in the chamber comprising a pair of opposed hook elements, one of said hook elements being electrically connected with one terminal of said light and arranged for connection with one 65 terminal of the battery, and means for effecting

a connection between the other battery terminal and the said bottom section, comprising a flexible member pressed inwardly from the wall of the flange of the bottom section and normally spaced from the said other terminal, the other terminal of the light being in connection with the bottom section.

In testimony whereof we hereunto affix our signatures.

GILBERT C. ATWILL. 75
JAY O. BROWDER.
